Specification for Design.

Patented Dec. 19, 1916.

Application filed September 22, 1916. Serial No. 121,680. Term of patent 7 years.

To all whom it may concern:

Be it known that we, ROBERT Y. BARROWS and GEORGE V. STRAHAN, citizens of the United States, residing at Rutherford, in the county of Bergen, and Newark, in the county of Essex, both in the State of New Jersey, have invented a new, original, and ornamental Design for a Shade for Lighting-Fixtures, of which the following is a specification, reference being had to the accompanying drawing, forming part thereof.

showing our new design. Fig. 2 is a fragmentary bottom plan view of the same. Fig. 3 is a fragmentary horizontal section thereof taken on line 3—3, Fig. 1.

We claim:

The ornamental design for a shade for lighting fixtures, as shown.

ROBERT Y. BARROWS.
GEORGE V. STRAHAN.
